UNITED STATES PATENT OFFICE.

JOHN O. CARREY, OF ST. LOUIS, MISSOURI, ASSIGNOR TO C. & C. ENGINEERING COMPANY, INC., OF ST. LOUIS, MISSOURI, A CORPORATION OF MISSOURI.

GYRATORY PUMP.

Application filed March 15, 1928. Serial No. 94,733.

My invention relates to gyrator pumps, the objects of my invention being to generally improve upon and simplify the construction of this type of pump and to provide a relatively simple and easily operated device that is highly effective in the exhausting or compressing of air, gas, or other fluids.

Further objects of my invention are to provide a simple and efficient seal between the fixed and movable parts of the gyratory pump so as to minimize the leakage of the fluid from the operating chamber and to provide simple valve means for controlling the passage of fluid from the operating or compression chamber.

Other objects of the invention are to provide a floating end plate for sealing one end of the operating or compressing chamber, said end plate being movable laterally to open and close the outlet port of said compressing chamber so as to control the discharge of fluid therefrom to the high pressure chamber.

With these and other objects in view, my invention consists in certain novel features of construction and arrangement of parts, hereinafter more fully described and claimed, and illustrated in the accompanying drawings, in which—

Figure 1 is a horizontal cross section 30 through my gyratory pump.

Figure 2 is a vertical cross section taken on line 2—2 of Figure 1.

Figure 3 is a vertical cross section taken on line 3—3 of Figure 1.

Figure 4 is a vertical cross section taken on line 4—4 of Figure 1.

Figure 5 is a fragmental detail view similar to Figure 4 but showing the end plate in moved or closed position.

Figure 6 is a horizontal cross section taken through a modified form of my gyratory pump.

Figure 7 is a perspective detail view of the gate valve shown in Figure 6.

Figure 8 is a perspective view of the recess member adapted to receive the gate valve.

The invention is characterized by the use of a gyratory element preferably a circular or ring-shaped member that is arranged for operation within a suitable housing and actuated by means of an eccentric mounted on the driving shaft of the pump. The discharge of the fluid from the operating chamber of the pump is effected by a floating plate which is arranged adjacent to one end of said operat-

ing chamber and is actuated by means of an eccentric to open and close the discharge port of the pump in a predetermined relation with the movement of the gyratory element within said operating chamber.

Referring by numerals to the accompanying drawings, 10 indicates a cylindrical casing which forms the annular wall of the housing of the pump and is provided with annular flanges 11 and 12 which serve as heads or end walls for the housing. Head 11 is provided with a cylindrical extension 11^a in which is formed a high pressure chamber 13 which is closed by head 14. This head is provided with a hollow boss portion 15 in which is arranged a ball bearing 16 for receiving a shaft 17. Flange 12 of casing 10 is secured to a head 18 which, in the present instance, is provided with a bushing 19 for receiving the intermediate portion of shaft 17.

The gyratory pump illustrated in the drawings is of the two stage type and consequently shaft 17 extends through bushing 19 and has its end journaled in a bearing 20 which is located in the cap extension 21 of a head 22. 80 This head is bolted to a cylindrical extension 23 of a casing 10^a, the opposite end of said casing being secured to the other end of head 18. Cylindrical extension 23 forms a high pressure chamber 13^a which is similar in construction to chamber 13 and is located on the opposite side of the pump. The pump as illustrated in the drawings is designed to be used as a two stage compressor, casing 10 housing the primary or low pressure unit and casing 10^a housing the secondary or high pressure unit, casing 10 being reduced in width as shown in Figure 1.

An eccentric 25 is fixed to shaft 17 and extends the full width of compressing chamber A which chamber is formed by casing 10. A similar eccentric 26 is fixed to shaft 17 and operates in compressing chamber B of casing 10^a. However, eccentric 26 is offset with eccentric 25, being preferably one hundred eighty degrees apart from said eccentric 25. Loosely arranged on eccentric 25 is an eccentric 27 and this last mentioned eccentric is set at an angle to eccentric 25 and is self adjustable so as to maintain the outer face of a gyratory element 28 in surface contact with the inner face of casing 10. This gyratory element 28 is loosely mounted on eccentric 27 by means of a roller bearing 29 which is interposed between said element and eccentric 27. 110

The fluid is drawn into chamber A through intake ports 30 formed in an enlargement 10^e of casing 10. A cap 31 is secured to enlargement 10^e and secures one end of a pipe connection 32 to said inlet ports 30. A gate valve 33 is slidably mounted in casing 10 and extends radially into chamber A and bears against the outer face of gyratory element 28. The inner end of said gate valve has fixed thereto a plunger 34 which operates in a bore 35, the outer end of which is closed by a screw plug 36. Gate valve 33 is held in fluid-tight contact with the inner face of element 28 by virtue of the fluid pressure created in bore 35 and exerting pressure against the inner end of pin 34.

As the shaft rotates in the direction indicated by the arrow in Figure 3, the line of contact between the gyratory element 28 and the inner face of casing 10 gradually advances from the inlet openings 30 toward gate 33, thereby placing the fluid contained in the upper half of chamber A or the fluid contained between the gate valve 33 and the line of contact between the gyratory element 28 and casing 10 under pressure at the same time forcing it out from chamber A through a duct 37 formed in the upper face of gate 33 into gate chamber 38 from which it then escapes into high pressure chamber 13, one end of gate chamber 38 communicating with an arcuate groove 39 which latter is formed in the face of flange 11 to facilitate the discharge of the compressed fluid into high pressure chamber 13.

This arcuate slot or discharge port is controlled and adapted to be closed by a circular plate 40 which bears against the face of flange 11 and receives gyratory motion to open and close port 39 in proper time relation with the operation of gyratory element 28 in chamber A. The gyratory movement is imparted to circular plate 40 by means of an eccentric 41 which is fixed on shaft 17 to one side of eccentrics 27 and 25 and is disposed at a suitable angle to said eccentrics to insure proper positioning of plate 40.

From high pressure chamber 13 the compressed fluid is conveyed away by a pipe connection 42. In the two stage compressor pipe connections 42 are connected to the inlet port of casing 10^a as shown in Figure 1 and discharge the partially compressed fluid to chamber B where it is compressed by a gyratory element 43 which is mounted by means of roller bearings 44 on an adjustable eccentric 45, the latter being mounted on fixed eccentric 26.

A gate valve 46 is arranged in chamber B and has fixed thereto plunger 47, which operates in bore 48, the latter being closed by a screw plug 49. A groove 50 formed in the upper face of gate valve 46 admits the compressed fluid from chamber B into the gate

chamber 51 from which it is then discharged through an arcuate groove 52 into high pressure chamber 13^a and a pipe connection 53 conveys the fluid away from chamber 13^a. A circular plate 54 which is similar to plate 40 is mounted on an eccentric 55 and opens and closes discharge port 52 in correlation with the operation of gyratory element 43 in chamber B.

To prevent escape of fluid from high pressure chambers 13 and 13^a along the shaft outwardly to the atmosphere, or to the compressing chambers, each head 14 and 22 is provided with inwardly extending tubular portions 56 which terminate a short distance from circular plates 40 and 54 and carry seal rings 57 which are loosely arranged on said tubular extensions and have their inner ends bearing against circular plates 40 and 54. The outer ends of these rings 57 are provided with a series of apertures for receiving small coil springs 58 which are seated in said apertures and have their outer ends bearing against heads 14 and 52, thereby exerting slight pressure against rings 57 so that the latter are at all times in sealing contact with plates 40 and 54. These springs also have tendency through rings 57 to hold said plates 40 and 54 in sealing contact with the respective faces of casings 10 and 10^a.

A plurality of packing rings 59 is arranged in each peripheral face of tubular member 56 for insuring sealing contact between the respective faces of said tubular portions 56 and rings 57. In this manner, all danger of leakage of the fluid to the atmosphere is reduced to minimum and plates 40 and 54 are held to their seats by the pressure in chambers 13 and 13^a, while springs 58 serve to exert enough pressure against said plates 56 during the starting operation of the compressor or when there is no pressure in said chambers 13 and 13^a. Casing 10 is provided with a series of outwardly extending projections or pins C which serve to dissipate the heat produced during the operation of the compressor.

A duct 60 leads from each compressing chamber A to bore 35 and admits fluid thereto so that plunger 34 is placed under pressure and holds partition wall member 33 in proper contact with gyratory member 28. Eccentrics 27 and 46 are automatically adjustable on eccentrics 25 and 26, respectively, so as to maintain gyratory members 28 and 23 in proper contact with the internal faces of the respective compressing chambers.

As the shaft 17 rotates in the direction indicated by the arrow, the point of contact of each gyratory member and the face of the respective compressing chamber advances toward each partition wall member, thereby compressing the fluid contained in said chamber between these points and expels said fluid from said chamber under pressure through

passageways formed in the high pressure sides of the respective partition wall members. In the first stage of compression, the fluid is expelled through passageway 37 into recess 38 from which it escapes through the arcuate groove 39 into high pressure chamber 13. A pipe connection 42 conveys the fluid away from the high pressure chamber 13.

- 10 When the fluid is discharged from the high pressure side of the compressing chamber a new discharge of fluid is drawn into the low pressure side through pipe connection 32 and intake ports 30. When the high point of 15 gyratory member 28 during its gyratory movement engages partition wall 33, the latter is retracted into recess 38, thereby closing passageway 37 to the compressing chamber. Simultaneously with this or in proper time 20 relation with the positioning of member 33, member 40 is actuated to close slot 30 so that high pressure chamber 13 is sealed against communication with the compressing chamber A. After the high point of member 28 25 leaves member 33 and passes intake ports 30, member 33 is projected into the compressing chamber a sufficient distance to permit passageway 37 to communicate with the compressing chamber A.
- 30 The movement of plate 40 may be timed so as to open the groove 39 at a predetermined time during the movement of gyratory member 28 or after the fluid contained in the high pressure side of the compressing chamber has 35 been placed under sufficient pressure.

When the device is to be used as a vacuum pump, pipe connection 32 is connected to the chamber to be placed under vacuum, while pipe connection 42 may be left open to the atmosphere.

10 In the form shown in Figures 6 to 8, a gyratory member 61 is provided with a radial projection 62 which operates in a recess 63 formed in the wall of the compressing chamber. This projection 62 is adapted to move inwardly and outwardly in recess 63 and the lower face 62^a of said projection is at all times in contact with face 63^a of said recess in order to prevent passage of fluid from the high pressure side of partition member 62 to the low pressure side thereof. The upper face of member 62 is provided with a groove or passageway 64 for facilitating admission of fluid from the compressing chamber into recess 63. An arcuate groove 65 leads from recess 63 into the high pressure chamber 66 and is adapted to be closed by an end plate 67, the operation of which is similar to end plate 40. Member 62 is preferably formed removable from gyratory member 61 as shown in Figure 7, said gyratory member being provided with a seat 68 for receiving said member. Recess 63 is formed in a block 69 which is seated in a 65 pocket 70 formed in the wall of the compress-

ing chamber and is removable therefrom as shown in Figure 8. By making members 62 and 69 removable they can be manufactured more accurate and at less expense and can be cast hardened if necessary.

70 A device of my improved construction is efficient in operation, occupies very little space, and can be coupled directly to the motor.

75 While I have shown the preferred forms of my improved pump, it is obvious that various changes in the construction and arrangement of parts can be made and substituted for those herein shown and described without departing from the spirit of my invention as expressed in the appended claims.

I claim:

1. In a gyratory pump a casing provided with a compression chamber, an eccentrically mounted member arranged for gyratory movement in said chamber for compressing fluid therein, an element mounted so as to project into said chamber and be retracted therefrom to maintain contact with the periphery of said member, an outlet duct in 85 said element and leading into a high pressure chamber arranged in said casing, an outlet passage leading from said pressure chamber outwardly through one end of said casing, and a gyratory plate operable independently of 90 and in correlation with said gyratory member for controlling said outlet passage.

2. A gyratory pump comprising in combination a casing provided with a compression chamber, an eccentrically mounted member 100 arranged for gyratory movement in said chamber for compressing fluid therein, an element in engagement with the wall of said chamber and with said member and movable in a radial direction to provide a partition wall in said chamber, said element being provided with a discharge duct leading from said compression chamber into a high pressure chamber formed in said casing, an outlet passage opening from said high 105 pressure chamber through one end of said casing and a gyratory plate operable independently of and in correlation with said gyratory member for controlling said outlet passage.

3. A gyratory pump comprising a casing having a cylindrical compression chamber, a fluid inlet port and a fluid outlet port arranged in said casing and opening into said chamber, a gyratory member disposed in said chamber and cooperating with the inner face thereof, a plate in engagement with the wall of said chamber and with said gyratory member thereby forming a partition wall in said chamber separating said inlet and outlet ports, and an end plate for sealing one end of said chamber and operable to open and close said discharge port.

120 4. A gyratory pump comprising a casing having a cylindrical compression chamber 125

and provided with inlet and outlet ports, a centrally arranged shaft extending through said chamber, a gyratory member disposed in said chamber in cooperative relation with the 5 inner face thereof and operatively carried by said shaft, a slideable plate mounted in said casing and extending into said chamber in engagement with said compression chamber, a high pressure chamber formed in one end 10 of said casing and having said outlet port opening thereinto, an end plate disposed in said high pressure chamber, an eccentric fixed to said shaft and carrying said plate and adapted to operate the latter to open and 15 close said outlet port in correlation with the operation of said gyratory member.

5. A gyratory pump comprising a casing having a cylindrical compression chamber and provided with inlet and outlet ports, a 20 centrally arranged shaft extending through said chamber, a gyratory member disposed in said chamber in cooperative relation with the inner face thereof and operatively carried by said shaft, a slideable plate mounted 25 in said casing and extending into said chamber in engagement with said gyratory member to form a partition wall in said compression chamber, a high pressure chamber formed in one end of said casing and having 30 said outlet port opening thereinto, an end plate disposed in said high pressure chamber, an eccentric fixed to said shaft and carrying said plate and adapted to operate the latter to open and close said outlet port in 35 correlation with the operation of said gyratory member, a head for closing said high pressure chamber and provided with an inwardly extending annular flange, a sleeve arranged exteriorly of said flange and in 40 sealing contact with said plate, and packing rings interposed between the cooperating surfaces of said sleeve and said flange.

6. A gyratory pump comprising a casing provided with a cylindrical compression 45 chamber and a high pressure chamber, a gyratory member arranged in said compression chamber, an end plate in said high pressure chamber for closing one end of said compression chamber, said end plate being adapted to 50 be acted upon by the fluid pressure in said high pressure chamber to maintain a fluid tight seal with said compression chamber, and a discharge passage leading from the high pressure side of said compression chamber 55 into said high pressure chamber.

7. A gyratory pump comprising in combination a casing provided with a cylindrical compression chamber and a high pressure chamber, a shaft journaled in said casing and 60 extending through said chambers, a gyratory member carried by said shaft and operating in said compression chamber, a radially movable partition wall cooperating with said gyratory member and engaging a recess 65 formed in the wall of said compression cham-

ber, a circular plate arranged on said shaft in said high pressure chamber, a passageway leading from the high pressure side of said compression chamber into the recess of said partition wall, and a discharge port leading 70 from said recess into said high pressure chamber whereby said end plate is adapted to be acted upon by the fluid pressure in said high pressure chamber to maintain a fluid tight seal with the end of said compression 75 chamber.

8. A gyratory pump comprising in combination a casing provided with a cylindrical compression chamber and a high pressure chamber, a shaft journaled in said casing and 80 extending through said chambers, a gyratory member carried by said shaft and operating in said compression chamber, a radially movable partition wall cooperating with said gyratory member and engaging a recess 85 formed in the wall of said compression chamber, a circular plate arranged on said shaft in said high pressure chamber, a passageway leading from the high pressure side of said compression chamber into the recess of said partition wall, a discharge port leading from 90 said recess into said high pressure chamber whereby said end plate is adapted to be acted upon by the fluid pressure in said high pressure chamber to maintain a fluid tight seal 95 with the end of said compression chamber, and means operated by said shaft for actuating said end plate to open and close said discharge port in correlation with the operation of said gyratory member.

9. In a device of the class described a casing provided with a cylindrical compression chamber and having a high pressure chamber arranged at one end, a head for closing said high pressure chamber, a shaft extending 100 through said chambers and having bearings in said head and in said casing, a gyratory member carried by said shaft and operating in said compression chamber, a valve member 105 movably mounted in said compression chamber and engaging said gyratory member, an intake port leading to the low pressure side of said compression chamber, a discharge port leading from the high pressure side of said compression chamber, an end plate 110 arranged on said shaft in said high pressure chamber for sealing said compression chamber and adapted to be held thereagainst by the fluid pressure prevailing in said high pressure chamber, and a sleeve interposed between said plate and said head for exerting 115 yielding pressure against said plate, there being an extension formed on said head for supporting said sleeve in position.

10. In a device of the class described a 120 casing provided with a cylindrical compression chamber and having a high pressure chamber arranged at one end, a head for closing said high pressure chamber, a shaft extending through said compression chamber 125

- and having bearings in said head and in said casing, a gyratory member carried by said shaft and operating in said compression chamber, a partition wall member movably interposed between the inner face of said compression chamber and said gyratory member, an intake port leading to the low pressure side of said compression chamber, a discharge port leading from the high pressure side of said compression chamber, an end plate arranged on said shaft in said high pressure chamber for sealing said compression chamber and adapted to be held thereagainst by the fluid pressure prevailing in said high pressure chamber, a sleeve bearing plate for exerting initial pressure thereagainst, there being an extension formed on said head for supporting said sleeve in position and resilient means interposed between said sleeve and said head.
11. In a device of the class described a casing provided with a cylindrical compression chamber and having a high pressure chamber arranged at one end, a head for closing said high pressure chamber, a shaft extending through said compression chamber and having bearings in said head and in said casing, a gyratory member carried by said shaft and operating in said compression chamber, a partition wall in said compression chamber engaging said gyratory member and slideable into a recess formed in the wall of said compression chamber, an intake port leading to the low pressure side of said compression chamber, a discharge port leading from the high pressure side of said compression chamber, an end plate arranged on said shaft in said high pressure chamber for sealing one end of said compression chamber and adapted to be held thereagainst by the fluid pressure prevailing in said high pressure chamber, a sleeve interposed between said plate and said head for exerting initial pressure against said plate, a flange projecting inwardly from said head for supporting said sleeve, and packing rings in said flange for sealing the joint therebetween and said sleeve.
12. In a device of the class described a casing provided with a cylindrical compression chamber, a shaft extending through said chamber, an eccentric fixed to said shaft, a second eccentric loosely arranged on said first eccentric, a ring loosely mounted on said second eccentric and adapted to gyrate within said compression chamber in tangential contact with the inner face thereof, a plate radially disposed between said gyratory member and the wall of said chamber and forming a partition wall in the latter, said member being provided with a passage on its high pressure side, a discharge port communicating with said passage, and an intake port leading into said compression chamber on the low pressure side thereof.
13. In a device of the class described a cas-
- ing provided with a cylindrical compression chamber, a shaft extending through said chamber, an eccentric fixed to said shaft, a second eccentric loosely arranged on said first eccentric, a ring loosely mounted on said second eccentric and adapted to gyrate within said compression chamber in tangential contact with the inner face thereof, a plate radially disposed between said gyratory member and the wall of said chamber and forming a partition wall in the latter, said member being provided with a passage on its high pressure side, a discharge port communicating with said passage, an intake port leading into said compression chamber on the low pressure side thereof, and a gyratory plate carried by said shaft on one side of said compression chamber and adapted to open and close said discharge port.
14. In a device of the class described a casing provided with a cylindrical compression chamber, a shaft extending through said chamber, an eccentric fixed to said shaft, a second eccentric loosely arranged on the first eccentric, a ring loosely mounted on the second eccentric and adapted to gyrate within said compression chamber in tangential contact with the inner face thereof, a plate radially disposed between said gyratory member and the wall of said chamber and forming a partition wall in the latter, said member being provided with a passage on its high pressure side, a discharge port communicating with said passage, an intake port leading into said compression chamber on the low pressure side thereof, an end plate arranged in said casing adjacent to one end of said compression chamber and loosely carried by said shaft, said end plate being adapted to seal one end of said compression chamber, a head for closing the respective end of said casing and provided with an inwardly projecting flange, and a sleeve arranged on said flange and yieldingly held against said plate to maintain the latter under pressure against the end of said compressing chamber.
15. In a device of the class described a casing provided with a cylindrical compression chamber, a shaft extending through said chamber, an eccentric fixed to said shaft, a second eccentric loosely arranged on said first eccentric, a ring loosely mounted on the second eccentric and adapted to gyrate within said compression chamber in tangential contact with the inner face thereof, a plate radially disposed between said gyratory member and the wall of said chamber and forming a partition wall in the latter, said member being provided with a passage on its high pressure side, a discharge port communicating with said passage, an intake port leading into said compression chamber on the low pressure side thereof, an end plate arranged in said casing adjacent to one end of said compression chamber and loosely carried by said

shaft, said end plate being adapted to seal said end of said compression chamber, a head for closing the respective end of said casing and provided with an inwardly projecting 5 flange, a sleeve arranged on said flange and yieldingly held against said plate to maintain the latter under pressure against said compression chamber, and packing rings arranged on said flange and bearing against 10 said sleeve to form a fluid tight joint there between.

16. In a device of the class described a casing provided with a cylindrical compression chamber closed at one end and terminating at 15 the opposite end in a high pressure chamber, a removable head for closing said high pressure chambers and having bearings in said head and in said casing, a gyratory member carried by said shaft and operating in said 20 compression chamber, a longitudinal partition wall arranged in said compression chamber in engagement with said gyratory member and retractable into a recess formed in the wall of said compression chamber, an intake 25 port leading to the low pressure side of said compression chamber, a discharge port leading from the high pressure side of said compression chamber into said high pressure chamber, an end plate arranged on 30 said shaft in said high pressure chamber for sealing the open end of said compression chamber, and auxiliary means for yieldingly exerting pressure against said plate to maintain it in sealing contact with said compression 35 chamber during the starting operation, said plate being adapted to be held against said end of said compression chamber by the fluid pressure prevailing in said high pressure

chamber when the device attains its normal operating pressure.

17. In a device of the class described a casing provided with a cylindrical compression chamber closed at one end and terminating at the opposite end in a high pressure chamber, a removable head for closing said high pressure chamber, a shaft extending through said compression chamber and having bearings in said head and in said casing, a gyratory member carried by said shaft and operating in said compression chamber, a partition wall arranged in said compression chamber in engagement with said gyratory member and retractable into a recess formed in the wall of said compression chamber, an intake port leading to the low pressure side of said compression chamber, a discharge port leading from the high pressure side of said compression chamber into said high pressure chamber, an end plate arranged on said shaft in said high pressure chamber for sealing the open end of said compression chamber, auxiliary means for exerting yielding pressure against said plate to maintain it in sealing contact with said compression chamber during the starting operation, said plate being adapted to be held against said end of said compression chamber by the fluid pressure prevailing in said high pressure chamber when the device attains its normal operating speed, and means operable in correlation with said gyratory member for actuating said end plate laterally to open and close said discharge port.

In testimony whereof I hereunto affix my signature this 26th day of February, 1926.

JOHN O. CARREY.
